UNITED STATES PATENT OFFICE

1,987,132

BABY BOTTLE HOLDER

Thomas Shine, United States Navy, Norfolk, Va.

Application January 26, 1934, Serial No. 708,484

3 Claims. (Cl. 248—65)

The present invention relates to improvements in baby bottle holders and has for an object to provide an improved holding device for a baby's milk bottle that will relieve a busy mother or nurse of the physical strain and time required in feeding a baby with a baby bottle. Another object of the invention is to provide an improved device of this character which will be susceptible of attachment at a variety of positions along the side of a baby crib with the bottle holder enabled to assume various angular positions and positions of various elevations in order to bring same to a convenient location for feeding the baby in either recumbent or sitting postures.

15 A further object of the invention is to provide a simple and inexpensive device for accomplishing the above stated purposes which will be easy of application and adjustment to the crib and to the baby's position.

20 With the foregoing and other objects in view, the invention will be more fully described hereinafter and will be more particularly pointed out in the claims appended hereto.

In the drawing wherein like symbols refer to like or corresponding parts throughout the several views,

Figure 1 is a fragmentary perspective view of the side of a baby's crib with the improved device applied thereto.

30 Figure 2 is an enlarged cross sectional view taken through the bottle holder substantially along the line 2—2 in Figure 1.

Figure 3 is a similar view taken at substantially right angles to Figure 2, and

35 Figure 4 is a plan view of the bottle holder with the straps and the flexible cable broken away.

Referring more particularly to the drawing, 5 designates generally the clamp of U or other 40 shape adapted to be slipped over the rail 6 of the side of a crib and to be moved therealong to any desired position. The clamp may be tightened by a screw 7 or other device.

Extending upwardly from the clamp is a plate 45 8 having a semi-cylindrical portion 9 for receiving therein one end of a flexible cable 10 which is clamped to the plate 8 by a companion clamp plate 11, the plates being held together by the use of screws or other fastenings 12.

50 The inner sides of the clamp jaws 13 and 14 may be covered with baize or other material to avoid scratching or marring the finish of the cradle. The flexible metal cable 10 will be similar to that employed with flexible desk lamps 55 which permits of movement in any direction pos-

sessing sufficient stiffness to retain the cable in the adjusted position.

The free end of the cable is affixed in a sleeve 15 which is brazed, welded or otherwise affixed to a spring, horse-shoe shaped bottle holder 16 made of light flexible metal or similar material and having an open mouth at one side to receive a bottle 17 containing milk or other fluid. At the mouth of the holder the sheet metal is coiled outwardly as indicated at 18 in order to provide 10 flaring spring jaws for moving apart when the bottle 17 is introduced between the jaws and of thereafter closing with a light spring pressure upon the bottle sufficient to hold the bottle against accidental removal from the holder. 15

The sides of the holder carry buckles 19. These buckles, as shown in Figures 2 and 3, are secured near one end of the holder and preferably at approximately 90° from the sleeve 15. The buckles are adapted to adjustably receive the 20 free end portions of straps 20, such straps being secured to the guard 21. The guard consists of a hemisphere of soft rubber, such as would be produced by cutting a hollow rubber ball in half and with the circular edge stiffened by a hard 25 ring 22 of rubber or the like. The straps 20 are attached to this reinforced circular edge 22 at diametrically opposite points. The diameter of the hemisphere may be about five inches.

In the center of the convex surface of the 30 hemisphere is an opening 23 large enough to permit the neck of the baby bottle 17 passing therethrough.

The rubber of the hemisphere is flesh colored and soft to simulate a mother's breast, the nipple 35 24 of the bottle projecting through the center.

In the use of the device the bottle is filled and the nipple put on. The bottle with nipple on is then inserted in the holder 16, the neck of the bottle passing through the hole 23 in the guard 40 21 which remains attached to the holder 16, unless it is desired to remove it for cleaning. The guard 21 is attached to the holder by means of straps 20, which engage with the buckles 19. The buckles may be of the prong type and minor 45 adjustments of the position of the bottle may be made by means of these straps, but the guard is securely attached to the holder and may not be pulled away.

The straps 20 may be about four inches in 50 length. The flexible cable is preferably about two feet long. This flexible cable permits of bringing the guard and bottle in a center plumb line of any crib or cradle and by twisting the cable permits the bottle holder to lie in the ver- 55

tical plane of the center line at any angle desired to the horizontal plane of the crib or cradle and as far above the horizontal plane as desired within limits.

5 It will be obvious that various changes in the construction, combination and arrangement of parts may be made which could be used without departing from the spirit of my invention, and I do not mean to limit the invention to such details except as particularly pointed out in the claims.

Having thus described my invention, what I claim and desire to secure by Letters Patent of the United States is:—

15 1. A baby bottle holder comprising a clamp, a flexible cable carried by the clamp, a bottle holder supported adjustably by the cable for receiving a baby's bottle, a guard carried by the holder, straps on the guard and buckles on the holder for adjustably receiving said straps.

20

2. A baby bottle holder comprising a clamp, a flexible cable supported by the clamp, a holder for a baby's bottle having a nipple, a hemispheric guard having an opening to receive the neck of the bottle and formed with a circumferential reinforced edge, straps attached to the reinforced edge at substantially diametrically opposite points, and buckles on the holder for adjustably receiving said straps.

5

3. A baby bottle holder comprising a clamp, a flexible cable supported by the clamp, a spring metallic holder for a baby's bottle having an opening at one side thereof with rounded curled jaws bent back from the opening, a sleeve attached to the holder for receiving the free end of the cable, a hemispheric soft rubber guard carried by the holder, and means for removably attaching said guard to the holder.
